WILLIAM A. HARRIS, OF BOSTON, MASSACHUSETTS, ASSIGNOR, BY MESNE ASSIGNMENTS, TO THE PATENT AND LICENSING CORPORATION, OF BOSTON, MASSACHUSETTS, A CORPORATION OF MASSACHUSETTS

ROOFING AND METHOD OF FORMING THE SAME

Application filed August 13, 1924. Serial No. 731,775.

Comparatively thin roofing, such, for example, as that formed of sheet material as felt, saturated and coated with asphalt and with or without a granular surfacing material, when laid in overlapping courses, whether in strip form or in individual shingles, presents a somewhat flat appearance on the roof which is often objectionable. Its appearance may be much improved, however, 10 by producing an optical effect of shadows along the lower edges of the courses.

According to this invention the desired optical effect is produced by cutting the lower edge of the material of each course in zig-zag or serrated formation, the serrations preferably being of such small size that when laid 15 they do not appear from a distance as serrations, but do act to broaden out the actual zone of shadow produced by these edges 20 and give the appearance of a band of shadow of a width corresponding to that produced by the edge of material of substantially greater thickness than that of the material actually used. The effectiveness of this shadow effect 25 is further heightened by causing the serrations to be somewhat irregular, the irregularity being sufficient so that no repeated pattern of irregularity is noticeable. By this means the effect of substantial roughness in 30 the surface of the material is produced. A shadow effect may be produced by tearing off the lower edge of the exposed roofing material. This, however, is not only a time consuming procedure, but it results in substantial 35 waste of material and it leaves exposed raw edges of the material which are inadequately protected from the weather by the saturating and coating materials and thus more rapid deterioration of the roof results. 40 By cutting the material as hereinbefore described the effect desired is obtained to a greater degree than is possible by the torn edges, and without waste or the other serious objections inseparable therefrom.

Where individual shingles are desired one edge may be serrated and the other not, this furnishing a ready indication of their top and bottom edges. Asphalt or similar shingles having a granular surfacing rolled in are 45 found to have a grain effect conforming to

the direction of rolling and if some shingles are laid in one direction relative to this grain and some in another over different areas of the roof, a splotchy effect is likely to result from the different color tone effects due to the different positions relative to this grain that the different portions of the roof are viewed. 55

With this invention, particularly as applied to strip shingles, the units may be cut without waste and in a manner which insures all the units being laid with the grain running in the same direction, or if desired they may be cut so that adjacent units as cut and packaged will have the grain running in opposite directions so that the different grain effects will alternate in relatively small sections producing a pleasing mottled instead of an unpleasant splotched effect. 60

Another variation, particularly applicable to individual shingles, each having one end serrated and the other end plain or with a different pattern of serrations producing less shadow effect, comprises laying these units alternately with the corresponding edges down and up, the shadow effect thus being 70 more pronounced at every other element, giving the effect of alternately relatively thick and thin elements, this effect being further heightened in case the grain of the grit surfacing is reversed in adjacent units of each 75 course to present alternately different color shades or tones. The serrated edges may also be employed to designate by their patterns the particular factory making and selling the roofing, certain patterns being restricted to 80 certain factories, though the variations in pattern may be so small as to be unnoticeable to the ordinary observer of the roof, but apparent to one closely inspecting any of the 85 elements. 90

For a more complete understanding of this invention, reference may be had to the accompanying drawings in which

Figure 1 is a diagrammatic side elevation of mechanism for cutting sheet material into 95 lengthwise strips each with one serrated edge.

Figure 2 is a fragmentary elevation of a pair of cooperating slitting rolls for the mechanism of Figure 1.

Figure 3 is a fragmentary perspective of a 100

rotary chopping knife for cutting the lengthwise strips into individual shingle elements.

Figure 4 is a perspective of one of the shingle elements.

5 Figure 5 is a plan of a portion of the sheet material showing the manner in which the units may be cut therefrom.

Figures 6 to 9 are views similar to Figures 1 to 3 and 5, respectively, but showing the 10 units as cut crosswise from the sheet material.

Figure 10 is an elevational detail of the zigzag cutter portion of the roller shown in Figure 9.

15 Figure 11 illustrates in perspective a package of roofing elements.

Figures 12, 13 and 14 are perspectives showing various applications of the invention to strip shingles.

20 Figure 15 is a perspective of a portion of the roof laid up with individual or strip shingles formed according to this invention.

Figure 16 is a similar view illustrating a different manner of laying individual shingles.

25 Figures 17 to 20 inclusive are perspectives illustrating different manners of cutting strip shingles from the sheet material.

Referring first to Figures 1 to 5, the sheet 30 roofing material is shown as in roll form at 1 from which it is unwound and passes between cutting rollers 2 and 3 which split it into sections of the desired width. As illustrated in Figure 2 each alternate slitting knife 35 is formed zigzag as at 4, the intermediate knives 5 being plain. This zigzag is preferably of irregular cutline so that the web as shown in Figure 5 is cut along irregular zigzag lines as at 6 and is slit midway between 40 these lines as at 7. The material then passes to the rotary chopping knife 10 which cuts the narrow strips crosswise along the lines 11 of Figure 5 to form individual shingle elements each having one edge 12 serrated 45 and the other edges plain as illustrated in Figure 4. Where the units are cut in this manner it will be seen that half face in one direction and half in the other relative to the sheet from which they are cut, assuming that 50 the serrated edge is the lower end of each unit. As the grain of the surfacing, provided granular surfacing material is rolled into the sheet material, runs lengthwise of the web, it runs crosswise of each shingle unit, as the 55 units are designed to be laid vertically with their serrated edges depending the grain is crosswise of the units in all instances, though running in one direction on some and in the opposite direction on others. The color tone 60 when these shingles are viewed at distances is not greatly different on all, and the shingles being packaged as they are cut in a manner to cause the grain on each alternate one to be reversed any splotchy color effect when laid is 65 avoided.

Instead of cutting the shingles crosswise of the web, as hereinbefore described, they may be cut lengthwise as shown in Figures 6 to 9. When this is to be accomplished the web is slit by circular slitting knives 20 70 on slitting rollers 21 and 22 and is then cut laterally into the desired units by a chopping roller such as is illustrated in Figure 8 at 25. As shown this roller is provided with two 75 chopping knives, one of these, as 26, being straight, and the other, as 27, being irregularly serrated. This knife 27 may be made up from sheet steel and set in a lengthwise groove in the roller 25 which is then filled on either side of the knife 27 to complete the 80 circular contour of the roller by easily fusible metal such as babbitt, as shown, for example, at 28 in Figure 10. With this form of cutter each alternate cross cut is irregularly serrated as shown at 30, while intermediate 85 cross cuts are straight as illustrated at 31. This mechanism produces groups of shingle 90 elements cut from each longitudinally disposed narrow strips, alternate units facing in opposite directions relative to the grain of the surfacing, which in this instance will be pronounced since as laid certain shingles will be viewed in the direction of the grain and certain in the opposite direction. They may be packaged, however, as shown in Figure 11. 95 with the two groups of shingles alternately disposed so that when the shingles are laid with their serrated edges all downwardly exposed as shown, for example, in Figure 15, 100 they will present alternately different color tones. If desired, however, as previously pointed out, each alternate shingle may be laid with its serrated edge down, the intermediate shingles being laid with the straight 105 end down, as shown in Figure 16. In this case if the grain of the shingles is disposed differently relative to the serrated ends a uniform color effect will be produced, but an effect of shadow giving the illusion of elements of relatively greater and less thickness 110 will be produced. If desired, also, shingle 115 units might be cut each having a serrated and a straight end and cut with the grain running in the same direction on all so that when laid alternately with the serrated and straight 120 edges exposed alternate color tones are presented. Of course where it is desired to cut the shingles all in the same direction relative to the grain of the surfacing it can not be done without waste unless both of the oppositely disposed edges are to be serrated.

In Figures 12 to 14 are shown strip shingles cut so that both the upper and lower edges are serrated. In Figure 12 the pattern presented is a series of irregularly spaced serrations 35, the spaces between the points being greater than the points themselves. In Figure 13 the serrations 36 take the form of a curved or waved effect and are of quite substantial size relative to the size of the units, 130

while in Figure 14 the serrations 37 are small and closely spaced, giving an irregular saw tooth effect to both upper and lower edges. In each of these instances the strips may be 5 cut in the same way relative to the grain of the material since the upper edge of one unit may be complementary to the lower edge of the adjacent unit as illustrated in Figures 17 and 18 where the strips are cut crosswise and 10 longitudinally respectively of the web of sheet material. Where straight upper edges are desired the units may be cut from the material either crosswise, as shown in Figure 19, or lengthwise as shown in Figure 20. In 15 this case it will be noted that alternate strips face oppositely relative to the grain of the material. Of course instead of cutting the material as drawn from a roll, it might be cut as received directly from the saturating 20 and coating mechanism as is commonly done.

By the terms "finely serrated" and "of relatively small size" used in the claim as applied to the serrations, I mean serrations of sufficiently small size so that when the shingles 25 are in position on a roof, these serrations are substantially indistinguishable as such to the ordinary observer, but present rather the appearance of a widened shadow zone beneath the butt ends of the units of each course.

30 Having thus described certain embodiments of this invention it should be evident to those skilled in the art that various changes and modifications might be made therein without departing from its spirit or scope as 35 defined by the appended claim.

I claim:

40 A roofing unit having a serrated lower edge, said serrations comprising triangular projections of such a size as to be substantially indistinguishable as such at the ordinary distance of an observer from a roof, the edges of said projections thus blending to present a shadow effect wider than that cast by a straight edge of the same material.

45 In testimony whereof I have affixed my signature.

WILLIAM A. HARRIS.
